UNITED STATES PATENT OFFICE.

CHARLES REISTLE, OF BROOKLYN, NEW YORK, ASSIGNOR TO CHARLES F. A. HINRICHES, OF SAME PLACE.

LAMP-BURNER.

SPECIFICATION forming part of Letters Patent No. 240,763, dated April 26, 1881.

Application filed February 18, 1881. (No model.)

To all whom it may concern:

Be it known that I, CHARLES REISTLE, of Brooklyn, in the county of Kings and State of New York, have invented an Improvement in 5 Lamp-Burners, of which the following is a specification.

This burner is adapted to the kind of lamp known as the "student-lamp," but instead of the burner being a fixture, as has heretofore 10 been usual, the same is removable, and the wick is raised and lowered by a ratchet or toothed wheel.

In the drawings, Figure 1 is a vertical section of the lamp-burner complete. Fig. 2 is a 15 plan at the line xx . Fig. 3 is a section of the removable chimney-holder and cone separate from the rest of the burner; and Fig. 4 is a plan of the drip-cup separately.

The oil is supplied by the pipe a from the 20 reservoir to the space between the burner-tube b and air-tube c , as usual, and d is the drip-cup.

At the upper end of the burner-tube b there 25 is a screw-collar, e , that receives the base f of the removable burner. Above this base f there is a tube, g , similar to the tube b , rising as high as the top of the air-tube c , and around the same is the ring h , forming a support for the 30 wick raiser or ratchet k , that has a button-head, as usual, and it acts through a slot in the tube g .

Within the tube g there is a wick-raising 35 tube, l , having holes for the points of the ratchet-wheel k to act in when raising or lowering the wick n . The wick n is to be attached to this tube l by means of small spurs turned inwardly from the metal of the tube, or by being sewed into holes near the bottom, or by the lower end of the tube being slotted for the 40 wick to be sewed to the bars between the slots; or, if the wick is flat and rolled into a cylindrical form there may be an inner ring connected to the tube l , so that the wick can be tied around the same. By this construction 45 the burner and wick can be unscrewed and taken off the burner-tube for inserting or removing the wick, and the wick will be raised bodily and uniformly by the action of the tube l and ratchet, and the lamp can be cleaned

with facility when necessary. The oil must 50 not rise above the level of the screw-collar, but should stand about one inch below the same.

The chimney-holder m and the cone o are removable from the burner-tube. I have improved the same by making this removable portion m in two pieces, so that they are cheaper 55 and stronger than heretofore.

The gallery-ring s , that is perforated and provided with a central opening, is in one piece with the chimney-holding spring m , the same 60 being drawn up by dies and cut to the proper shape, and the cone o is adapted to set around the tube g , and it is slotted or perforated for the passage of air to the flame, and its base is a horizontal flange, the edge of which is received into the recess formed at the junction of the gallery-ring and chimney-holder, so that 65 the two parts are connected at this point. The cone and chimney-holder are easily removable from the burner-tube, and the gallery-ring 70 forms a guide to steady the parts at the bottom.

The drip-cup is made so that the accumulation of oil in the same will not close the air-openings, as sometimes is the case when the 75 oil is forced over by carelessness. This I accomplish by extending the top of the drip-cup conically and cutting holes in the same that extend to a higher level than the edge of the drip-cup, so that the holes will remain open 80 when the oil overflows from the cup. This will prevent the oil catching fire, as sometimes happens when the ordinary drip-cup is full and the air-holes become closed.

The capillary attraction sometimes causes 85 the oil to draw over and run down the outside of the burner-tube, and it may spread upon and drip from the outside of the drip-cup. I prevent this by the downward projections 10 inside the drip-cup, either in the form of lips 90 turned down below the holes or as a downward flange. The oil draws down and drips into the cup from the lower edges of these downward projections, instead of spreading upon the outside of the drip-cup.

I claim as my invention—

1. In an Argand burner, the combination, with the air-tube c , burner-tube b , and drip-

cup *d*, of the screw-collar *e*, removable tube *g*, and wick-raising wheel *k*, substantially as set forth.

2. The combination, with the removable 5 burner-tube *g* and wick-raising wheel *k*, of the wick-raising tube *l*, having a row of holes for the wick-raiser, and the wick secured to the said tube, substantially as set forth.

3. The removable gallery-ring and chimney- 10 springs formed of one piece of metal, said gallery-ring being perforated and adapted to surround the burner-tube, in combination with the perforated cone adapted to fit the burner-

tube at the upper end and connected at its lower edge to the metal of the chimney-holder 15 and gallery, as set forth.

4. The combination, with the drip-cup, of the downward projections 10 within such drip-cup, for the purposes and as set forth.

Signed by me this 8th day of February, A. 20 D. 1881.

CHARLES REISTLE.
